UNITED STATES PATENT OFFICE.

OSCAR SNELL, OF WILLIAMSBURG, OHIO.

IMPROVEMENT IN PRUNING-SHEARS.

Specification forming part of Letters Patent No. 124,455, dated March 12, 1872.

SPECIFICATION.

I, OSCAR SNELL, of Williamsburg, in the county of Clermont and State of Ohio, have invented certain Improvements in Pruning-Shears, of which the following is a specification:

The nature and object of my invention are such that by the combination of the blade A, Fig. 1, with its connection B to the pitman F and lever E, results the drawing cut upon the top of the limb, a motion most preferable in instruments of this class, together with cheapness, durability, and lightness.

Similar letters of reference indicate corresponding parts.

Figure 1 is a side view of an instrument embodying my improvement. Figs. 2 and 3 are detached views of the movable and stationary blades A and C, with connection B of blade A. Fig. 4 is the screw that connects the blades.

D, Fig. 1, is the handle or pole, of any desired length, into which the stationary blade C is driven. A is the movable blade, turning on the screw H. F is the pitman, of length to

suit the pole D, connecting the blade A and lever E. I is the fulcrum or pivot upon which the end of lever E turns, and connects the same to the handle B.

It is obvious that, by pressing downward on the lever E, the edge of the blade A will be drawn toward the edge of the stationary blade C with a drawing cut in proportion as the edge of the blade A is made nearer the periphery of the circle having H as the center, with the end of the blade P touching its circumference.

Claim.

I claim—

The construction of blade C in such manner that pivot H is removed to one side, the limb resting directly over the center of the pole, to prevent the same from springing, the projecting point of the blade C colliding with the top of pitman F, to prevent the opening of blade A, for the reception of limbs beyond its strength to cut, the whole arranged as described.

Witnesses: OSCAR SNELL.
